[57] **CLAIM**

I claim the ornamental design for the sailor's suit, as shown and described.

DESCRIPTION

FIG. 1 is a right rear perspective view of a sailor's suit showing my new design, the rear left being a mirror image thereof;

FIG. 2 is a front right perspective view thereof, the front left being a mirror image thereof, and the broken lines around the front chest panel being understood to represent stitching; and,

FIG. 3 is a front perspective view thereof shown in an alternate position.
